UNITED STATES PATENT OFFICE.

FRANKLIN SPAULDING, OF GALVA, ILLINOIS, ASSIGNOR OF ONE-THIRD TO ERNEST L. BENSON AND ONE-THIRD TO JAMES W. HOLMES, OF GALVA, ILLINOIS.

BUTTONHOLE-WORKING ATTACHMENT FOR SEWING-MACHINES.

1,000,126.

Specification of Letters Patent.

Patented Aug. 8, 1911.

Application filed October 10, 1910. Serial No. 586,310.

To all whom it may concern:

Be it known that I, FRANKLIN SPAULDING, a citizen of the United States, and a resident of Galva, in the county of Henry and 5 State of Illinois, have invented a new and useful Buttonhole-Working Attachment for Sewing-Machines, of which the following is a specification.

My invention relates to means attachable 10 to and removable from practically any of the various types of sewing machines, by the employment of which buttonholes may be rapidly and neatly worked without guidance of the material by the operator.

15 It will be manifest that various modifications and changes in the features of construction, in the combinations of parts, and in the arrangement and disposition of the 20 elements for coaction, may be made without departing materially from the essential scope of the invention.

I am aware that devices of this nature are in use, with varying degrees of success, but 25 all such as have come under my observation have some one or more objectionable features.

The principal object of my invention is, 30 therefore, to comprehensively and generally improve the construction, whereby more efficiency, greater capacity, and superior results will accrue.

Concisely stated, other objects of the invention are: to so construct and actuate the mechanism that the stitches at the end portions of the buttonhole, instead of being 35 "piled" (or worked into and over each other) whereby a thick, unsightly end is produced, as is the result or effect of the employment of all prior machines of this 40 nature of which I am aware, will be uniform, and the stitches regular and true.

The foregoing recited object I accomplish by providing an accelerator, whereby 45 the action in moving the cloth from one side of the buttonhole to the other, at each extreme of the longitudinal portion thereof, when the movement is on centers, is hastened by automatically lengthening the 50 stitch, (regulation of the stitch otherwise being a separate adjustment common to most all sewing machine attachments,) and whereby the action, when off centers, automatically reassumes its ordinary or normal adjustment as imparted to it by the stitch-regulator.

A further object is to provide novel means whereby the length of the buttonhole may be predetermined with certainty and accuracy.

A further object is to dispense with the use of a clutch-plate or the like having a pivot-aperture in which is arranged a pivot of materially less area than said aperture, whereby the action is rendered uncertain and ineffective.

To provide novel primary-actuating means, comprising a toothed lever and a segment plate, is another object of the invention.

To provide a simple, effective, and compact friction clutch for imparting movement to certain parts or elements of my improvements constitutes still another object.

To provide a novel arrangement of cams for imparting hereinafter specified movements to the cloth-feeding and directing means is still another object.

That the mechanism constituting the above recited means be durable, strong, simple, and not liable to disarrangement nor disability, is a prime requisite, and to provide such means for carrying out these ends constitutes another object.

Minor objects will be in part obvious and in part pointed out.

To the attainment of the foregoing ends 85 the invention consists in the features of construction and modifications thereof, and in the combinations of parts and arrangement and disposition of the elements for co-action, the scope of which will be pointed out in 90 the appended claims.

Coming now to a description of the accompanying drawings, which illustrate the invention as embodied in the best way now known to me, and in which the same reference numeral indicates the same part in the different figures:—Figure 1 is a top plan in which a portion of the movement or operation is illustrated by dotted lines; Fig. 2, a bottom plan; Fig. 3, an elevation, seen from 100 that edge which I shall herein designate as the "front"; Fig. 4, a fragment detail, a bottom plan illustrating one of the movements; Fig. 5, an enlarged detail, an inverted plan of the clutch mechanism; and Fig. 6, 105 an enlarged sectional detail in the line 6—6 in Fig. 5.

Prefatory it may be stated that in operating my device the throat-plate and feed-dog are covered by a suitable plate, thereby 110

allowing freedom of movement to the feed-dog while not permitting it to interfere with the fabric being operated upon, the latter moving unobstructedly over the work-plate 5 and beneath my attachment, and being guided by the serrated cloth-feeder in an evident manner.

2 represents a base or supporting-plate and is best shown at Figs. 1 and 2. Secured thereto and projecting vertically therefrom is a clamp or yoke 3, the position of which is selective in order that the attachment may be used with machines different from the one shown and of various constructions. 10 It is apertured for the reception of a thumb-screw 4 whereby it may be secured to the presser-bar of the machine, the presser-foot having first been removed. The base-plate supports at its rear portion a standard 5 15 which carries at its free end a pivot-pin 6 whereon a bell-crank lever 7 is mounted, the power-arm 8 of which lever is bifurcated and adapted for actuation by the needle-bar-screw of the machine, which screw it straddles, while the weight-arm 9 20 is provided with teeth or cogs 10 which engage those of a horizontally disposed segment plate 11 loosely mounted on a stud 12 which carries an oscillator-cam 13 (Fig. 4) 25 presently described. The parts of the machine hereinbefore referred to may be of any ordinary construction and need not be herein described; neither need they be illustrated. Fixed on the upper end of said stud 30 35 is a ratchet-wheel 13^a adapted for actuation by a pawl 14 pivoted to the segment and held in operative position by a spring 15.

Fulcrumed at 16 to the base-plate is a stitch-regulating and adjusting lever 17, the 40 tail of which is turned to provide an eye 18 into which is threaded an adjusting-screw 19. The point 20 of the weight arm of the lever 17 takes against the tail-piece of the angularly fashioned clutch-lever 21, the 45 front portion of which is reflexed to form a clip 22 which straddles a friction-loop 23 constituting one member of a friction-clutch. The clip and loop have pivotal connection by means of a pin 24, see Figs. 5 50 and 6.

26 indicates a hub provided with an annular peripheral groove 27 and with a constricted lower central portion 28 on which is fixed a switch-cam 29, (more fully presentedly described,) and an upper constricted portion 30 carrying a disk 31 provided with an eccentrically disposed threaded recess or aperture 32 for a purpose hereinafter described.

60 33 is a projection from the loop 23, and 35 is a resistance spring the respective end portions of which are engaged therewith and with a pin rising from the base-plate. The function of the spring 35 is the common one of drawing the loop or ring

23 from operative engagement with the grooved hub.

A link 36 is engaged by a pivot-screw 37 at one of its ends with the recess 32 and its distal end is similarly connected by a pivot-screw 38 with the projection 39 of a slotted rocker or adjusting-lever 40 of the second order, the bent end of which lever has pivotal connection at 41 with the base-plate. 70

42 denotes an equalizer or accelerator 75 pivoted at 43 to the base-plate and provided with an extension 44 to which is pivoted at 45 one end of a link 60, the other end of which has pivotal connection with the rocker 40 near its bend. While I have 80 shown in the principal figures a substantially triangular accelerator-plate provided with a projection 46 and valleys 47, it will be manifest that the general idea of my invention comprehends a much broader and 85 diversified scope.

Reference is now to be had more particularly to Figs. 2 and 4. 48 represents a feeder-plate provided with a longitudinal slot 49. At its outer end said plate has an 90 enlarged transversely arranged head 51 provided with a slot 52. The stem of a thumb-screw 53 passes loosely through the slots in the rocker 40 and in the head 51, for a purpose presently related. The front end of 95 the plate 48 is provided with fingers 54 beneath which is fixed a cloth-feeder 55 struck up from an oblong sheet of metal and provided with a central opening 56 within which the needle has play. Both the external portion thereof and the walls of the slot are continuously serrated, whereby the cloth will be firmly and unyieldingly held, no matter what the direction of the feeder-plate and feeder may be. The cams 13 and 100 29 are retained in operative positions within the slot 49 by means of a binding-plate 57 secured to the lower face of the base-plate by screws 58, 59.

I now proceed to the description of the 110 operation. Assume the parts to be in the relative position shown by full lines at Fig. 1. In this position the traveler or feeder-plate has traversed approximately one-half of its extreme path of movement and the 115 needle is plying along the central portion of one of the sides of the buttonhole being created. As the lever 7 is successively actuated as hereinbefore described, the teeth thereof will impart reciprocating rotary movements to the segment and thereby to the pawl, which, drawing with it the ratchet-wheel in its counter-clock-hand movement, will communicate like movement to the stud 12 which will in like manner impart intermittent rotary movements to the cam 13, and these movements will be converted into lateral oscillations of the feeder-plate and feeder to carry said plate into alternating contacts with the point of the ad- 120 125 130

justing screw, by which the distance between stitches is regulated as follows. Said cam throws the edge of the feeder-plate into successional contacts with the point of said screw at each impulse of said plate in the direction of said screw, and the point of the lever 17 will take against the tail-piece of the clutch-lever 21, the clip-end of which will cast forwardly the friction-loop 23 which will thereby engage the peripherally grooved portion of the hub 26 and throw it a minute part-rotation. Simultaneously therewith and thereby the link 36 will receive a forward impulse to impart movement to the rocker 40 and thereby through the instrumentality of the thumb-screw 53 impart longitudinal intermittent movement to the head 51. The same movement of the rocker will impart step-by-step movement in an evident manner to the link 60 and thereby to the accelerator 42. These movements being successively continued in a constant ratio, the parts will at the proper time assume the relative positions shown by dotted lines in the same figure, in which they are shown as occupying their positions of greatest traverse. In this position the switch-cam is midway between the longitudinal sections or side portions of the button-hole, and as its rotary movement is continued it brings the feeder-plate and feeder into position to guide or direct the fabric along one longitudinal section of the button-hole in process of formation, it being evident that when its cam-sides are traversing the respective walls of the slot, the feeder-plate will at each extremity of its movement be turned or switched across. In the dotted-line position above referred to, which I have hereinbefore referred to as "on center", the pendent point of the clutch-lever is lying in one of the valleys 47 of the accelerator, thus permitting said lever to take the full sweep of the lever 17 and thereby cause the distance between stitches to be automatically enlarged or augmented. It will be clear that the same effect will occur at the opposite end of the buttonhole when the motion is on center. As the link 60 throws the accelerator-plate extension 44 to the left (from the position shown by dotted lines at Fig. 1) the point 46—which is the arc of a circle of which the pin 45 is the center—coming into contact with the pendent point of the clutch-lever, will shorten the stroke or throw thereof and impart a shorter stroke to the link 36, whereby the resultant movements of the parts actuated thereby will be consequently lessened and the distance between stitches will again be the normal one.

That the stitch-regulator is actuated in one direction by the oscillations of the feeder-plate has hereinbefore been stated. It will be noted that each alternate throw

of the feeder-plate causes one bight or stitch to be formed. When it is desired to decrease the distance between stitches the screw 19 is to be turned to the left (or backward) to increase the distance between it and the 70 feeder-plate. The extent of movement of said plate being determined by the cam 18, it will be evident that as the screw is farther removed from said plate, the former will receive less motion or extent of travel and 75 consequently impart less throw to the clutch lever, thereby causing the feeder-plate to have a reduced longitudinal step-by-step movement at each impulse of the link 36. Bringing the said screw into closer relation- 80 ship to the feeder-plate will bring about a reverse movement and result.

To regulate the length of the buttonhole the thumb-screw 53 is adjusted toward the free end of the rocker to permit the head 85 51 to have greater longitudinal movement to thereby carry the feeder 55 a greater distance to form a buttonhole of greater length. A contrary adjustment of said screw will effect a contrary and evident result. 90

The ends of the buttonholes formed by the employment of my improvements are smooth, even, and of neat and attractive appearance. The distance between the attachment and the work-plate being variable at 95 the will of the operator, by means of the clamp-yoke, permits fabrics varying greatly in thickness to be successfully operated upon. The gear causes a positive and unfailing action, and the clutch being likewise 100 positive in its action, as well as simple, compact and strong, renders the action certain. The oscillating cam and the switch-cam are so timed with reference to each other, and so held within the slot 49 (which may be of 105 equal width throughout its length if preferred,) that no mistakes by reason of their failure to properly act can occur.

Having thus set forth the preferred construction, having stated the purposes and 110 objects and advantages, and having described the operation of the means shown, I claim as new and desire to secure by Letters Patent the following, to-wit:—

1. In combination, a cloth-feeder-plate, a 115 feeder carried thereby, a cam for imparting oscillatory movements to said plate, a stitch-regulator actuatable by said plate, a clutch-member actuatable by said regulator, a second clutch-member in engagement with the 120 one first recited, a link pivoted eccentrically to the last recited clutch-member, a rocker pivotally engaged by said link, means for pivotally connecting said rocker and feeder-plate, and means adapted to switch said 125 plate across the buttonhole in process of formation.

2. In combination, a cloth-feeder-plate, a 130 feeder carried thereby, a cam for imparting oscillatory movements to said plate, a stitch-

- regulator actuatable by said plate, a clutch-member actuatable by said regulator, a second clutch-member in engagement with the one first recited, a link pivoted eccentrically 5 to the last recited clutch-member, a rocker pivotally engaged by said link, means for pivotally connecting said rocker and the feeder plate, means adapted to switch said plate across the ends of the buttonhole in 10 process of formation, and means actuated by said rocker for regulating the extent of movement of said clutch.
3. In combination, a cloth-feeder-plate, a feeder carried thereby, means for imparting oscillatory movements to said plate, a stitch-regulator actuatable by said plate, a clutch-member actuatable by said regulator, a second clutch-member in engagement with the one recited, a link pivoted eccentrically 15 to the last recited clutch member, a rocker pivotally engaged by said link, means adjustably connecting said rocker and feeder-plate whereby the length of travel of the latter may be predetermined, and means adapted 20 to switch said plate across the ends of the buttonhole in process of formation.
4. In combination, a cloth-feeder-plate, a feeder carried thereby, a cam for imparting oscillatory movements to said plate, a stitch-regulating lever actuatable by said plate, means for varying the relationship between 25 said lever and plate, a clutch-member actuatable by said lever, a second clutch-member in engagement with the one first recited, a link pivoted eccentrically 30 to the last recited clutch-member, a rocker pivotally engaged by said link, means for adjustably connecting said rocker and plate, means adapted to switch said plate across the ends of the buttonhole in process of formation, and means 35 interposed between said rocker and the first recited clutch-member whereby the extent of movement of the clutch is periodically changed.

5. In combination, a cloth-feeder-plate 45 having a longitudinal and a transverse slot, an oscillatory cam disposed within said longitudinal slot and adapted to impart vibratory movements to said plate, a stitch-regulator actuatable by said plate, a clutch-member actuatable by said regulator, a second clutch-member actuatable by the one first recited, means for returning the clutch-members to their operative positions after each of said actuations, a link pivoted eccentrically to the last recited clutch-member, a slotted rocker in pivotal engagement with said link, adjusting means disposed in the slot in said rocker and in the transverse slot in said plate, an accelerator having variable contacts with the first recited clutch-member, a link interposed between said accelerator and rocker, and a switch-cam mounted in the longitudinal slot in said plate and actuatable by the second recited 55 clutch member.

6. In combination, a cloth-feeder-plate, means for imparting reciprocating longitudinal movements thereto, a stud disposed above and extending through said plate, a cam fixed on said stud and actuatable within a slot in said plate to impart vibratory movements thereto, a toothed segment loosely mounted on said stud, a ratchet-wheel fixed on the upper end of said stud, a pawl pivoted on the segment, means for throwing it into engagement with the teeth of said wheel, and a toothed lever adapted for engagement with and to actuate said segment.

In testimony that I claim the foregoing as my invention I hereunto subscribe my name in presence of two subscribing witnesses.

FRANKLIN SPAULDING.
